CLAIM

The ornamental design for a mobile telephone case, as shown and described.

DESCRIPTION

FIG. 1 is a back view of a mobile telephone case; FIG. 2 is a front view of the mobile telephone case; FIG. 3 is a perspective back view of the mobile telephone case; FIG. 4 is a perspective front view of the mobile telephone case; FIG. 5 is a right side view of the mobile telephone case; FIG. 6 is a left side view of the mobile telephone case; FIG. 7 is a top view of the mobile telephone case; and, FIG. 8 is a bottom view of the mobile telephone case. The broken lines depict portions of the mobile telephone case that form no part of the claimed design.
